[57] CLAIM

The ornamental design for a combined AM/FM radio,
torch blinder and beam light with clip, as shown and
described.

DESCRIPTION

FIG. 1 is a front elevational view of a combined
AM/FM radio, torch blinder and beam light with clip
showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view thereof, shown with
the top portion in an extended position.

FIG. 1

FIG. 2

FIG. 3

FIG. 4
